BENJAMIN LOUIS TOQUET, OF WESTPORT, CONNECTICUT.

SPARKING IGNITER FOR GAS-ENGINES.

SPECIFICATION forming part of Letters Patent No. 737,532, dated August 25, 1903.

Application filed April 3, 1902. Serial No. 101,256. (No model.)

To all whom it may concern:

Be it known that I, BENJAMIN LOUIS TOQUET, a citizen of the United States, and a resident of Westport, in the county of Fairfield, State of Connecticut, have invented Improvements in Sparking Igniters for Gas-Engines, of which the following is a specification.

The object of my invention is to improve the construction and operation of gas-engines, more especially with reference to the igniting mechanism and the control thereby of the speed of the engine.

While my present improvements have been designed mainly for use on a two-cycle gas-engine fed with gasoline, my improvements are applicable to other types of gas-engines. In the drawings I have shown my invention as embodied in a duplex or twin-cylinder engine; but it will be readily understood that my improvements can be embodied in a single-cylinder engine.

In the accompanying drawings, Figure 1 is an end view of the engine. Fig. 2 is a side view of the engine, partly in section. Fig. 3 is a sectional view, drawn to a larger scale than Figs. 1 and 2, of a part of the igniting mechanism. Fig. 4 is a longitudinal section of the connections between the eccentric-rod and the guide-rod P. Fig. 5 is a view of a modification.

As is common in this class of engines, the explosive mixture admitted to the cylinder is ignited by an electric spark produced at electrodes within the cylinder, one of these being a fixed electrode N, Fig. 2, carried by but insulated from the cylinder, and the other being a movable arm N', fixed on a shaft n', passing through a bearing in the wall of the cylinder and having on the outside an arm n''. When such an engine as this is used in a launch, the spray is liable to form a short circuit between the exterior of the cylinder and the outwardly-projecting end of the electrode. To prevent this, I provide a hood n, which covers and protects the insulating-joint between the cylinder and the electrode.

My improved means for actuating the movable electrode will now be described, each cylinder being equipped with a pair of electrodes and actuating means.

On the main shaft is an eccentric O, which actuates an eccentric-rod O', connected, as

hereinafter described, by a stud O² to a vertically-reciprocating slide P, working in guides P² in the frame. At the upper end of this slide P are two hinged fingers p p, normally pressed against the body of the slide by springs p' p'. Directly over this is an actuating-rod Q for the movable electrode, this rod being guided in a socket Q' on the engine-frame by means of a collar q and a sleeve q', the collar being fixed to or forming part of the rod, while the sleeve q' can slide on the rod Q. Between these two collars is a helical spring S. To the extreme upper end of the rod Q is fixed a head or collar q². The forked end of the arm n² for the movable electrode embraces the rod between the sleeve q' and collar q², so that when the rod Q is pushed up by one of the fingers p on the rise of the sliding rod P the arm n² will be pushed upward until the movable electrode N' comes into contact with the fixed electrode N in the cylinder. The continued upward movement of the rod will only serve to compress the spring S between the collar q and the sleeve q', forcing the movable electrode N' into firm contact with the fixed electrode N until that finger p which is supporting the rod is moved to one side by means hereinafter described, whereupon the spring S will start the rod Q down, the top collar q² will hit the arm n², and the rod Q, arm, and movable electrode will drop, making a positive quick break at the electrodes inside the cylinder. The end of the downstroke of the rod Q is prevented from being a destructive hammering stroke by reason of the bottom of the socket Q' being sufficiently closed to act as a dash-pot, a small outlet x allowing a slow escape of the air from within the dash-pot. By this construction of electrode-actuating means I require the use of but one spring.

The upper end of the slide P is provided with two hinged fingers p p, but only one acts at a time, one coming into use when the engine is running in one direction and the other when it is running in the other direction. The means for throwing the operating-finger p out of engagement with the rod Q at the proper moment in the upstroke of the slide P comprise an extension o' on the upper end of the eccentric-rod O', having a pin or projection o² projecting laterally in be-

tween the two fingers p p , and this eccentric-rod is pivoted at o^3 to the inner end of a link R, hung on a center r on the frame. I prefer to mount this center r on the frame eccentrically and to connect it to a hand-lever r' , so that the point of pivoting the link R to the frame may be thereby readily varied or adjusted. The eccentric-rod O' is connected to the vertically-reciprocating slide P by means of the stud O², which is fixed in the slide P. This stud passes through a slot (shown by dotted lines in Fig. 1) in the eccentric-rod O' and is fitted on its front end with a short horizontal slide-block O³, (shown partly broken away in Fig. 1,) guided in a horizontal groove in the face of the eccentric-rod O'. This connection gives the desired longitudinal reciprocating motion to the slide P, while allowing the connected eccentric-rod O' the needed swing on its pivot o^3 . On the other hand, the mounting of this pivot o^3 upon the link R allows the eccentric-rod to have a longitudinal as well as a swinging motion, so that the free upper end of the eccentric-rod has a path of motion somewhat like an ellipse and such that at a determined point in the upward travel of the slide-rod P the pin o^2 will trip or push the engaged finger p on its pivot out from under the rod Q, and the latter will then drop to break the circuit and make the ignition in the cylinder, as already described. By moving the hand-lever r' over laterally to adjust the pivoting center o^3 of the eccentric-rod through the link R the moment of ignition in relation to the stroke may be varied to suit requirements. In that way the speed of the engine may be governed or regulated very efficiently by the simple manipulation of the hand-lever r' . It will thus be seen that there are three characteristic features of the described eccentric mechanism for operating and tripping the igniting devices—first, there is the longitudinal reciprocating motion to bring the electrodes together and compress the spring S; secondly, there is the lateral or swinging motion of the free end of the eccentric-rod which trips or causes release of the spring and separation of the electrodes, and, thirdly, there is the lateral adjustment of the pivoting center of the eccentric-rod determining the point at which the spring shall be released and the ignition take place in the revolution of the engine. For the better understanding of this feature of my invention I have shown in Fig. 5 a modification in which the slide P is dispensed with and the tripping-fingers p p are mounted directly upon the free upper end of the eccentric rod O⁴. This form of eccentric-rod is slotted longitudinally to be free to move longitudinally on a slide Y, having a pivotal connection o^4 , with a horizontally-adjustable though stationary slide R', which thus takes the place of the link R. This pivotal connection o^4 thus forms the laterally-adjustable pivot for the eccentric-rod to determine the time at which the acting finger p shall be withdrawn from under the

rod Q by the lateral or swinging movement of the free upper end of the eccentric-rod.

I use the term "eccentric" in a sufficiently general sense to include a crank as its mechanical equivalent.

I claim as my invention—

1. In a gas-engine, the combination of the fixed electrode and the movable electrode with a rod to operate the movable electrode, an interposed spring on the rod and a socket surrounding the rod and spring and a dash-pot at the lower end of the socket, substantially as described. 75

2. In a gas-engine, the combination of the fixed and movable electrodes with a rod to actuate the movable electrode, an interposed spring, a socket in which said rod is guided, said socket being formed as a dash-pot for the return stroke of the rod and means for pushing the rod to close the circuit and compress the spring, and means for releasing the pusher. 85

3. In a gas-engine, the combination of the movable electrode with an actuating-arm, a sliding rod having a head and a fixed collar and free sleeve, a spring between the sleeve and collar with a socket in which the rod, collar and sleeve are guided, and which is formed as a dash-pot for the return stroke of the rod. 90

4. In a gas-engine, the combination of the movable electrode and its actuating-rod with a reciprocating slide having a pivoted finger, an eccentric-rod having an extended free end to act on the finger to disengage it from the actuating-rod of the electrode and a link to which the eccentric-rod is pivoted. 100

5. In a gas-engine, the combination of the movable electrode and its actuating-rod with a reciprocating slide having a pivoted finger, an eccentric-rod having an extended free end to act on the finger to disengage it from the actuating-rod of the electrode, a link to which the eccentric-rod is pivoted, a slotted connection between the slide and the eccentric-rod. 105

6. In a gas-engine, the combination of the movable electrode and its actuating-rod with a reciprocating slide having a pivoted finger, an eccentric-rod having an extended free end to act on the finger, a pivoting-link for the eccentric-rod and means for adjusting the pivot of the link, as and for the purpose described. 115

7. In a gas-engine, the combination of the movable electrode and its actuating-rod, with a reciprocating slide having a pair of pivoted fingers, an eccentric-rod having an extended free end to act on the two fingers, to free one or the other from the actuating-rod and a link to which the eccentric-rod is pivoted. 125

8. In a gas-engine, the combination of the movable electrode, and its actuating-rod, with a reciprocating slide carrying a pivoted finger, an eccentric-rod having an extended free end to act on the finger to disengage it from the actuating-rod, a link to which the eccentric-rod is pivoted, an eccentrically-mounted 130

pivot for the link and a hand-lever to adjust said pivot.

9. A gas-engine having as its means to actuate and trip its movable electrode, an eccentric and eccentric-rod with a pivot for the latter between the eccentric and its free outer end, means for moving said pivot laterally, and adapted to allow both longitudinal and swinging motion to the rod and a tripping-finger carried by and actuated by the free end of the rod, substantially as described. 25

10. A gas-engine having as its means to actuate and trip the movable electrode, an eccentric and eccentric-rod with a pivot for the latter near its upper end allowing it longitudinal and swinging motion, means for laterally adjusting said pivot and a tripping-finger actuated by the free end of the rod, substantially as described. 30

11. In a gas-engine, the combination of the movable electrode and its actuating-rod and

spring with an eccentric and eccentric-rod, a pivot for the latter, means for moving the pivot laterally, the rod thereby having both longitudinal and swinging motion and a tripping-finger actuated by the free end of the eccentric-rod, substantially as described. 35

12. In a gas-engine, the combination of the movable electrode and its actuating-rod and spring with an eccentric and eccentric-rod, a pivot for the latter, allowing it longitudinal and swinging motion, means for laterally adjusting said pivot and a tripping-finger actuated by the free end of the eccentric-rod, substantially as described. 35

In testimony whereof I have signed my name to this specification in the presence of two subscribing witnesses.
